CLAIM

The ornamental design for a "utensil," as shown and described herein.

DESCRIPTION

FIG. 1 is a perspective view showing a front and left side view of an ornamental design for a utensil;

FIG. 2 is a front view of the utensil shown in FIG. 1;

FIG. 3 is a right side view of the utensil shown in FIG. 1, the left side view being a mirror image thereof;

FIG. 4 is a rear view of the utensil shown in FIG. 1;

FIG. 5 is a top end view of the utensil shown in FIG. 1;

FIG. 6 is a bottom end view of the utensil shown in FIG. 1; and,

FIGS. 7-9 are perspective views showing a front and left side view of alternate embodiments of FIG. 1, the difference being the size of the utensil.
